ABSTRACT OF THE DISCLOSURE

An apparatus for producing copies of an original by the electro-photographic method in which the housing of the apparatus is divided into a number of superimposed zones. At one end of the upper surface of the housing a delivery slot is formed for discharging copies from the housing. Adjacent the delivery slot within the topmost zone in the housing is a fan which draws air into the zone through a vent hole at the opposite end with the air passing over heat emitting devices before combining with a radiation heater for improving the drying efficiency for the copies passing to the delivery slot.

The invention relates to an apparatus for producing copies, comprising an exposure device, a developing device, and a sheet feeding mechanism.

The said apparatus may comprise a control which initiates certain operational sequences automatically, especially with regard to the sheet feed mechanism and the application of an original to the exposure device. The exposure device provided comprises conveniently a transparent plate for the original and a transparent guide for the copying material to be exposed, with at least one light source, an objective and a deflecting mirror, as well as the exposure plate being arranged in the upper wall of the housing between these two parts.

More particularly, the invention relates to an automatic apparatus for producing copies according to the electro-photographic method.

It is already known, according to the electro-photographic method, to charge, expose and develop copying material and more particularly sheets of such material, whereupon the developing particles applied thereto, for example, pigments retained by electrostatic forces, are burned in for fixing the picture.

The present invention has the object of providing an automatic or automatically operating apparatus, wherein a compact construction is achieved by means of the mutual arrangement of its component parts, and wherein disadvantageous interacting effects are avoided.

It is a further object of the invention to provide an apparatus of the kind hereinbefore mentioned in which the performance can be particularly favourably utilized, particularly with regard to the thermal treatment of the copying materials and preferably the drying thereof.

According to the invention, these and related objects are realized by dividing the housing into four superimposed zones, separated at least partly by horizontal partitions, wherein the heat radiating devices, such as light sources, the drive motor, or a radiation heater, are arranged in the topmost zone, the developing device in the next lower zone, a horizontal chamber of the exposure device, terminating at the guide, in the third zone from the top, and finally at the bottom, divided by housing walls, the stacking arrangement for the copying material and roller arrangements for the cam controls.

It is an essential feature of the invention that the space of the topmost zone forms an air channel leading to a

delivery device for the copying material at the rear of the apparatus with a fan located in front thereof, and in that a flow of cooling air enters through an opening in the front of this chamber, carrying along the heat from the heat radiating devices towards the radiation heater so that its efficiency is increased. In this way, the heat generated in the apparatus is additively and functionally used for producing a copy. This novel feature is of relevant importance.

Preferably, the delivery device extends upwardly over the top of the apparatus in the form of a chimney, giving rise to a particularly favourable air flow.

The whole construction of the automatic apparatus has a particularly favourable ventilation, wherein the thermal effects of radiating parts, such as the motor, may be easily evacuated and functionally utilized, by being applied additively to the radiating heater which effects the fixing of the picture.

The invention will be further described, by way of example, with reference to an embodiment shown in the accompanying drawing, in which:

FIG. 1 shows a sectionalized side elevation of the apparatus, indicating merely the parts necessary for explaining the present invention;

FIG. 2 is a flow diagram.

FIG. 1 shows the apparatus generally. Levers of the control device are located in another plane parallel to the plane of the drawing than, for example, the chambers acting as guides for the sheet material.

“Rollers,” “transport rollers,” “dividing or guide walls,” and other elements or parts arranged in the housing, are located and fixed in housing side walls extending parallel to the plane of the drawing. Rollers may be so-called disk rollers, having disks or sections arranged on the same shaft, wherein individual disks may be offset relative to disks of adjacent rollers so as to produce parts which can be brought into and out of engagement with each other.

The term “drive motor” used in the following description, includes both the power source and the switching means required for producing the driving motion.

The automatic device according to the invention has a housing, comprising an upper surface 1, a front 2, a rear wall 3, a bottom plate 4, which may be equipped with legs 5 and 6. The upper surface 1 has holes 7, 8, 9, 10 therein, through which project guide rollers 11, 12, 13, 14 mounted in side walls of the housing, extending parallel to the plane of the drawing; these guide rollers protrude beyond the said upper surface 1 with a peripheral section, amounting, for example, to 1 or 2 millimetres.

Between the said holes 7, 8, and the guide rollers 11, 12, the upper surface is equipped with a transparent exposure plate 15, having a width at least equal to that of the copying material to be processed, and over which an original to be copied is guided.

The exposure plate is irradiated from below by at least one light source 16 arranged within the housing, for example by a tubular lamp, arranged in a reflector 17 which directs the radiation towards the exposure plate 15, but is located outside the picture beam, indicated by a dash-dot line 18. This beam impinges on a deflecting mirror 19, arranged, for example, on a three-point suspension on a plate 19' fixed in the housing. The beam passes via the mirror 19 through an intermediate partition or wall 20, having an orifice 21; this orifice has a width corresponding to the picture beam. Behind the mirror 19, there is an objective lens 22.

The exposure beam has an L-shaped configuration and passes along a horizontal path 23 to a guide surface 24, which is also transparent in the same way as the exposure plate 15. The substantially vertically located guide surface 24 defines a channel with the upper wall 20 and the lower wall 25. These walls define between themselves the hori-

zontal section of the L-shaped exposure beam towards the top and bottom between wall portions of the housing, extending parallel to the plane of the drawing and mounted on the housing walls. In addition, the guide surface 24 defines also a section of a transport path for the copying material, passing through the housing and described more fully further below.

The exposure device comprises contact rollers 26, 27 arranged above the guide rollers 11, 12 arranged in a housing-shaped frame and held in contact by means of a spring.

It is merely mentioned that, for example, the lower rollers 11, 12 and the said rollers 13, 14, as well as other revolving parts described further below, are driven by a drive, comprising a cable 29, guided on the rollers and driven by a motor 30. The motor may also comprise the power source for its operation. The contact rollers 26, 27 are mounted in oblong holes 62, 63 of the frame 28 and are urged in a downward direction by spring means 64. These spring means 64 rest in their centre on an abutment 65 in the housing 28 and press with their outer end on the shafts or stub shafts of the contact rollers 26, 27. The said housing-shaped frame 28 may be mounted detachably on the upper surface 1 of the main housing.

The upper zone of the housing forms a space above a shutter plane 31, shown only in part, with a motor 30 arranged thereabove, adapted to drive the revolving parts of the apparatus by means of a cable drive 29.

The developing section 58 is located underneath this part 32.

As may be seen from FIG. 1 the development device 32 is mounted on the partition 20. A cover 33 has an opening 34 above which is arranged the delivery socket of a storage tank 35 for developer fluid or for pigment. The container may be opened from the outside by known means, for example by a push button.

Under the partition 25 is a chamber, accessible through a flap 36 hinged at 66 to the front wall 2, and containing a drawer-shaped container with a stack 37 of sheets of copying material. This drawer-shaped container may have the form of a slide, consisting of a base plate 67, side walls 68 and an end wall, shown, for example, at 38.

A joint 69 is arranged on the base plate 67 and carries a pivotable stack support plate 70. This plate 70 is anchored via springs 71 on a support 72 arranged in upwardly projecting lugs 73 of the side walls 68, for example, in the form of a bar bridging the stack. Moreover, the stack side walls 68 are connected by a rod-shaped support 74, against which the top sheet of the stack is pressed when the stack is outside the housing.

A stop limits the movement of the slide into the housing. The slide is associated with actuating means, shown generally at 39, for removing the top sheet from the stack 37. Several rollers are mounted in assembly walls, located parallel to the side walls; these rollers form part of the unit 39. Above the inserted stack 37 near its end, located substantially in the centre of the housing, there is an intermittently actuatable delivery roller 75, which is freely rotatably mounted and acts on the topmost sheet of the stack. The lower peripheral section of the roller 75 is slightly lower than the support 74.

As viewed in the direction of movement of the material, downstream of the stacking mechanism, there is the said unit 39, forming the start of a transport section, equipped with upper and lower guides 76, 77, equipped with perforations. Through these perforations extend portions of driven rollers 78, 79 and a contact roller 80, and a control cam roller 81, respectively. These rollers are mounted in the housing side walls. Pivotal about the shaft 82 of the contact roller 80 is a lever 83, equipped with a mounting for a spindle 84 and a drive disk 85, driven continuously by the contact roller 80. The arrangement of the control disk 85 is such that, when the end 86 of the lever 83, projecting from the housing wall, is rotated downwardly, the said control disk 85 makes contact with

the delivery roller 75. The lever 83 is pulled in the upward direction by a spring 87 fixed in the housing.

The control unit will not be described in detail. It need only be mentioned that the control cam roller carries out its control functions by means of linkages 88 movable about the fixed spindle 87, on the one hand, in order to keep closed the switch 89 after the end 86 of the lever has been released, and on the other hand, in order to release the exposure device 7 from a lock, connected by a link 90 with the linkage system 83.

From the parts of the unit 39, a track with the guide member 92 and drive and transport rollers 93, 94 for the sheet of copying material leads to the guide 24 where an original is exposed on to the sheet of copying material. Further transport rollers 95, 96 and guides 91 lead from the said guide 24 to the inlet 40 of the developing device 32.

It should be pointed out that the unit 39 may also comprise elements, such as a charging device 41, where electro-photographic material is to be processed. Above the outlet 42 of the developing device, there is a pair of transport and squeeze rollers 43, 44 which are also driven by the cable drive 29. Above these rollers, the transport path continues between guide members 45, 46, 47 to the driven pairs of rollers 48, 49. Particularly the said guide element 45, but preferably also the other guide elements, are equipped with perforations. They may consist of strips, wires or perforated plates. Above the said guide member 45, the radiation heater 50 is arranged, for example in a reflector 51 or at a certain direction of radiation, so as to heat the guide path.

A fan 52 is arranged within the zone of the guide members 46, 47 between the assembly walls, delivering drying air obliquely upwardly in the direction indicated by the arrow 53. Within the zone of and above the rollers 48, 49, the whole housing has a chimney-like raised projection 54 with a leftwardly directed delivery slot 55. Transport rollers 56, 57 driven as indicated by the arrows, are mounted in front of this delivery slot. Between the pairs of transport rollers 48, 49, and 56, 57 there are preferably vertical, web-shaped or wire-shaped guide members 58, which permit the flow of air in the vertical direction and guide the copying material to the rollers 56, 57.

The rollers 48, 49, 56, 57, are, as also the other rollers in the apparatus, preferably disk-type rollers, permitting a flow of air to pass therethrough.

It should be pointed out that the upper housing compartment has, behind an air inlet 59, arranged at the top of the front wall 2, a chamber containing in sequence upstream of the radiation heater 50 the heat generating parts of the apparatus, namely the light source 16 and the motor 30. The arrangement of the fan 52 at the end of the chamber results in an air flow in the direction of the arrows 60.

Preferably, the device is used for processing electro-photographic material, but the drawing shows only the parts essential for explaining the present invention. Thus, the connection for connecting a charging station 41 to a high voltage source or the like, are not shown, because known means can be used for this purpose.

Under the delivery slot 55 are support bars 61, along which the delivered copying material is advanced, and between which the sheets can be easily gripped. These bars are arranged in spaced relationship, parallel to each other, extending from the bottom edge of the slot 55.

FIG. 2 shows diagrammatically the electric circuit. Several circuits are connected to the terminals, the parts of which are marked with the same reference numerals as in FIG. 1. The circuits with the parts 16, 30, 50, 52 are operable by a switch 99 not shown in detail in FIG. 1, when the apparatus is taken into use. The charging device 41 is adapted to be switched on by a separate switch 89 indicated as such in FIG. 1. The electrical connections 70 are shown in FIG. 2.

The L-shaped exposure beam is determined by the picture beams 18 and 23, so that it can be seen that the horizontal section, located laterally between side walls of the apparatus, is closed on the top and bottom by partitions 20, 25 and by the guide 24. The controls and driving components 83 through 88 and 90 are laterally of the chambers for the exposure beam. Of importance is the configuration of the upper zone of the arrangement above the surface 31, located in the housing side walls, or its extension, determined, for example, mainly by the cover 33 of the exposure device 32. The parallel upper zone in the housing under the top cover 1 is accessible from the front through at least one opening 59, through which air may enter in the direction of the row of arrows 60, carrying along the heat generated by the light source 16, the motor 30 and the radiation heater 50, and escaping under the action of the fan 52 into the chimney 54. The upwardly directed construction of the chimney 54 supports not only the escape of heated air towards the top to the delivery slot 55, but also ensures that the copying material passing through the chimney is exposed to the hot air on both sides so that a maximum effect is produced with the smallest possible fan performances.

I claim:

1. An apparatus for producing copies from an original on copying material, comprising a housing having an upper surface, side walls, a front wall and a rear wall; said housing being arranged to contain an exposure device having a vertically extending part, a developing device, a sheet feeding mechanism, driving means including a drive motor and transport components with said drive motor being arranged for driving said components for transporting copies and the original in the apparatus, light sources for the exposure of the original, a radiation heater for treating the exposed and developed copying material, a stacking device for the copying material adjacent said sheet feeding mechanism; a plurality of at least partially extending horizontal partitions disposed within said hous-

ing and dividing the interior thereof into a plurality of superimposed zones including a topmost zone being arranged to contain a number of heat emitting devices and said radiation device; said front wall of said housing having a vent hole therein opening into the topmost zone within said housing; said upper surface of said housing having a delivery slot therein communicating with the topmost zone and being located at the opposite end of said topmost zone from the vent hole; said upper surface of said housing comprising a transparent support for originals being positioned at the opposite end of said upper surface from said delivery slot, said transparent support forming the upper end of the vertical part of said exposure device; a fan disposed within the topmost zone in said housing and being located at the end of said housing adjacent the delivery slot whereby said fan is arranged to draw air into said topmost zone through the vent hole in the opposite end of said housing for absorbing heat from the heat emitting devices located within the topmost zone and for combining the heated air with said radiation heater for thus improving the efficiency of the treatment of the exposed and developed copying material.

2. An apparatus, as set forth in claim 1, wherein said upper surface includes a chimney-like upwardly directed projection extending over the width of said upper surface at the opposite end thereof from said transparent support, and said projection communicating with the topmost zone and containing the delivery slot from said housing.
